ATTORNEY

UNITED STATES PATENT OFFICE

JOSEPH A. MALLOTT, OF SEATTLE, WASHINGTON

INSOLE

Application filed December 31, 1926. Serial No. 158,280.

This invention relates to an insole, the general object of the invention being to provide the sole with means for supporting parts of the foot, after the manner of metal arch supporters and to so form the sole that it can be manufactured to sell at a much lower cost than can the metal arch supporters.

A further object of the invention is to make the device from absorbent paper or pulp and to provide it with antiseptic properties.

This invention also consists in certain other features of construction and in the combination and arrangement of the several parts, to be hereinafter fully described, illustrated 15 in the accompanying drawings and specifically pointed out in the appended claim.

In describing my invention in detail, reference will be had to the accompanying drawings wherein like characters denote like or 20 corresponding parts throughout the several views, and in which:—

Figure 1 is a plan view of the device, showing portions of the foot in dotted lines thereon.

25 Figure 2 is a side view.

Figure 3 is a section on line 3—3 of Figure 1.

Figure 4 is a section on line 4—4 of Figure 1.

30 Figure 5 is a section on line 5—5 of Figure 1.

Figure 6 is an end view.

In these views, 6 indicates the pad which is formed of absorbent paper or pulp and has 35 incorporated therein any well known materials which will give it antiseptic properties. Adjacent the front portion of the pad, a curved rib or raised portion 7 is formed which extends transversely across the pad or sole and is so arranged that it will fit in the space beneath the toes. The inner side is provided with an upwardly extending flange 8 which forms an arch support and a substantially egg-shaped enlargement 9 is formed 40 about the middle of the pad slightly in advance of the instep portion to form a support for the metatarsus arch.

From the foregoing, it will be seen that I have provided an inner sole which can be 45 manufactured to sell at low cost so that it

can be thrown away after one or two days' use, and one which will support different portions of the foot. By making it of absorbent material, it will collect moisture from the foot and thus will keep the bottom of the feet 55 dry and warm. By incorporating medicinal material in the sole or pad, it will have antiseptic properties. The pad can be made of any desired thickness so that it will conform with the foot on which it is to be used and 60 as the foot improves, the pad can be changed and another one substituted which is made to conform to the improved condition of the foot.

It is thought from the foregoing description that the advantages and novel features 65 of my invention will be readily apparent.

I desire it to be understood that I may make changes in the construction and in the combination and arrangement of the several parts, 70 provided that such changes fall within the scope of the appended claim.

What I claim is:—

An insole comprising a pad formed of absorbent material and having a central enlargement thereon forming a support for the metatarsus arch, an upwardly extending flange at one side thereof forming an arch support, a rib extending transversely across the front end of the pad in an irregular line 75 to fill the space under the toes, said rib being gradually reduced in thickness from one end thereof throughout its entire length, and medicinal material incorporated in the pad.

In testimony whereof I affix my signature. 85
JOSEPH A. MALLOTT.
